CLAIM

The ornamental design for a snack tray, as shown and described.

DESCRIPTION

FIG. 1 is a top, front, and left side perspective view of a snack tray;

FIG. 2 is a bottom, front, and right side perspective view of FIG. 1;

FIG. 3 is a top plan view of FIG. 1;

FIG. 4 is a right side elevational view of FIG. 1; and,

FIG. 5 is a cross-sectional view taken along line 5-5 of FIG.

3.

The broken line representations in the views are for illustrative purposes only and form no part of the claimed design.
